signors to The Aerotorque Company, Cleveland,
Ohio, a corporation of Connecticut

Application March 25, 1941, Serial No. 385,056

6 Claims. (Cl. 103—173)

This invention relates to a structurally and functionally improved pressure apparatus and in its more specific aspects aims to provide a unit of this character, which may either be constructed to primarily function as a pump, or else may have its parts arranged so that it will be of particular utility when employed as a hydraulic motor.

While the present apparatus may be utilized in numerous different associations, it will be of a special value when employed in aircraft, in that, it will be relatively compact, of light weight and involve a positive and reliable action, such that entire dependence may be placed upon its functioning.

It is an object of the invention, to furnish an apparatus by means of which, under constant R. P. M., variable displacement or pressures may be achieved when the unit functions as a pump; this object being in addition to the objects of light weight, compact structure and reliability of operation as set forth in the preceding paragraph.

A further object of the invention is that of designing a mechanism, in which the pistons may have a variable stroke; the control of such pistons being achieved in a novel and desirable manner.

An additional object is that of providing a regulating mechanism which may form a part of the unit and which according to the operating conditions encountered, the actuation of the control, as set forth in the preceding paragraph, may be entirely automatic.

A still further object is that of furnishing a pressure apparatus in which the valve mechanism will function in an entirely positive and desirable manner, such, that all avoidable leakage will be reduced to an utter minimum.

Another object is that of furnishing a pressure apparatus which may function, either as a pump or a motor and which apparatus embodies relatively few parts, each individually simple and rugged in construction; these parts operating over long periods of time with freedom from all difficulties.

With these and other objects in mind, reference is had to the attached sheets of drawings illustrating one practical embodiment of the invention, and in which:

Fig. 1 is an end view of the main portion of the apparatus but with certain of the parts illustrated in section; this view being taken along the lines 1—1 and in the direction of the arrows as indicated in Fig. 2;

Fig. 2 is a longitudinal sectional view of the apparatus;

Fig. 3 is a transverse sectional view taken along the lines 3—3 and in the direction of the arrows as indicated in Fig. 2;

Fig. 4 is a similar view taken along varying planes, however, but generally as indicated by the line 4—4 and adjacent arrows; and

Fig. 5 is an enlarged fragmentary and sectional plan taken along the lines 5—5 and in the direction of the arrows as also indicated in Fig. 2.

10 As afore brought out, the present teachings may be incorporated in a pump or hydraulic motor. As shown and as primarily described, it is presented in the former association. Also, the pump structure as herein traversed is intended 15 to develop relatively high pressures (for example, up to 3,000 lbs. to the square inch). At this time, it will be appreciated that the teachings of the present invention might be employed in connection with pumps which are to develop entirely different pressures and that this might readily be achieved with suitable modification of certain of the parts. Moreover, it is intended that in the drawings and following description, primary reference to a pump structure is to be taken in an illustrative rather than in a limiting sense except 20 where otherwise indicated in the claims.

Thus, referring primarily to Fig. 2, the numeral 10 indicates a driving shaft with which an oil seal 11 may be associated. This shaft is rotatably supported with reference to a mounting flange 12. The latter has secured to it—as for example by bolt 13—a guide block 14. A housing section 15 may in turn be mounted upon the block 14.

35 Shaft 10 extends into a tubular shaft 16 and a tight fit may be provided between these parts, so that they rotate as a unit. Additionally, they may be prevented from moving with respect to each other by means of a nut 18 mounted on the drive shaft and by a pin 17 which extends through both shafts. At this time, it will be observed that shaft 16 is also suitably supported by anti-friction bearings 19 and 20 and in fact, that bearing 19 may support shaft 10 through the intervening nut element 18.

40 A swashplate 21 is mounted on pin 17 and as especially shown in Fig. 5, spacing elements 22 may be interposed between plate 21 and the side faces of shaft 16. At the same time, it will be observed that the pin 17 is retained in position by means of securing elements 23 which engaged its end portions to effect this result. Thus, it is apparent that as shafts 10 and 16 are rotated the swashplate 21 will be correspondingly moved. 45 Also this plate may be freely oscillated with re-

spect to the axes of the shafts and incident to the pivot provided by pin 17.

A stop member 24 may be affixed to shaft 16 and extend outwardly, so that one limit of movement of the plate 21 will be to a position such, that it occupies a plane precisely perpendicular to the axes of the shafts 10 and 16. As illustrated, this stop member may be adjustable so that after assembly, the parts may be brought to exactly the desired positions and their further movement arrested so that this position may never be exceeded. The plate 21 may moreover mount, or have formed integrally with it arcuate rack portion 25. These are engaged by pinions 26 forming a part of a shaft 27 which is rotatably supported by and extends through shafts 10 and 16. As especially illustrated in Fig. 5, a layer of bearing material 28 may encircle shaft 27.

It is thus obvious, that if shaft 27 is rotated, plate 21 will be rocked while, if this shaft is retained against movement, the plate will be held in a fixed position of angularity with reference to the driving shaft. Now, to control the movement of shaft 27, it will be observed that in addition to the pinions 26 which may be integral with it, it may be formed with a central pinion portion 29. The teeth of the latter are engaged by a rack 30 which may form an integral part of a rod 31 slidably mounted in a bore formed in the end portion of shaft 10. Also, it will be observed that rod 31 may be provided with a flattened portion 32 which will have a configuration corresponding to that of this bore, so that there will be no danger of rotation occurring on the part of this rod with respect to shaft 10.

It is obvious that with the foregoing construction, a reciprocation of rod 31 will result in a rotation of pinion 29 and pinions 26. The latter meshing with the arcuate racks 25 will—as afore brought out—cause oscillation of the swashplate. The control of rod 31 may be effected in a number of different manners. However, the movement of this element, will in accordance with the teachings of the present invention, preferably be caused in a manner hereinafter more particularly described.

Returning to a consideration of Fig. 2, it will be noted that on the opposite side of the swashplate from the guide block 14, a cylinder and valve block 33 is provided. It is obvious that this block might be formed in any desirable manner of sections. It supports a housing 34 complementary to housing 15. A guide plate 35 is interposed between these housing sections and serves to centralize the same. Moreover, securing bolts 36 may be employed to retain the parts in assembled condition.

The guide block 14 is formed with a series of bores 37 and block 33 is likewise formed with a series of blind drilled recesses 38 which provide cylinders. As shown, the cylinders correspond in number to the number of bores which are provided and complementary bores and cylinders are furnished with their axes in alignment.

The swashplate 21 may, by means of bearing members 39, engage ball studs 40. One of the latter is mounted by each of connecting rods 41. These connecting rods are bowed or arched to extend around the periphery of the swashplate and may ride in grooves or slots 42 which interrupt the guide plate 35. Consequently, the connecting rod in reciprocating will have its motion guided so that it will not tend to swing. To one end of each connecting rod, a piston 43 is secured. To the opposite end of the same, a guide extension

44 is attached. These extensions and pistons, may of course, each be integral with the connecting rod. In any event, however, the guide portion 44 will ride within a recess 37 while the piston 43 will ride within a cylinder 38.

Assuming the swashplate to be angularly disposed, as illustrated in Fig. 2, it is apparent that as the shaft assembly 10—16 is rotated, the piston will be caused to reciprocate. In such reciprocation, a firm control of the parts will at all times be assured incident to the guide ring 35 or its equivalent structure as well as the guide portion 44, operating within the bore 37. As afore brought out, by shifting the rod 31, the angularity of the swashplate may be varied to increase or decrease the stroke of the parts. However, it is preferred that at no time shall such angularity exceed zero; this being assured by the stop element 24.

Now, in order to control the flow of fluid to and from the cylinders, a series of in-take controlling and outflow controlling valves are employed. A pair of these valves is furnished for each of the cylinders. One of the high pressure valves is indicated by the numeral 45 and one of the low pressure valves is indicated by the numeral 46. Each of these valves, includes a reduced edge portion cooperating with an adjacent seat portion in a manner such, that a line seal is preferably provided. Springs 47 normally urge these valves into seated condition. Adjacent their outer ends, they are guided or supported by means of sleeve elements 48. Eccentrics 49, either form a part of shaft 16 or are fixedly mounted thereon in line with the two series of valves. Tappets 50 are interposed between the valve stems 51 and the eccentrics 49. By varying these tappets or else by substituting tappets of different thicknesses, the position of the valves may be adjusted.

Beyond the block or block assembly 33, a manifold element 52 is provided. This may be secured in position by the bolts 36. A low pressure manifold 53 forms a part of the member or unit 52 and a high pressure manifold 54 likewise forms a part of this unit. A manifold sealing plate 55 may be interposed between unit 54 and block assembly 33; this plate being drilled to provide passages suitable for the flow of liquid. Bosses 55' are furnished which communicate with the high and low pressure manifolds and which may be coupled to any suitable supply and service lines (not shown). Gasket material may, of course, be employed throughout the entire assembly as indicated in the drawings. Also, suitable gasket material as indicated at 56 may be positioned within the bevelled cavities which are preferably of triangular cross-section and which are conveniently furnished adjacent the high pressure manifold 54. In this manner all probability of leakage from this manifold is prevented.

Turning to Fig. 4, it will be observed that the high pressure valve, there illustrated, controls the flow of fluid through a passage 57 which is disposed to one side of the bore within which the valve is mounted. This passage is connected to the high pressure manifold. It follows that with the parts constructed in the manner illustrated, and if the piston 43 is performing a working stroke, the force of the fluid which tends to lift the valve from its seat, will be counteracted by an equal force tending to seat such valve. Consequently, the valves of the high pressure series will act in a positive manner and function only in response to the shifting action of the eccentric 49. With the pressure forces acting on the valves

equalized, the springs 47 will normally maintain them in seated position.

Also, during the pressure stroke, it will be observed that fluid under pressure may flow through a passage 58 and act on the upper face of the low pressure valve 46. Consequently, to the sealing effect exercised by the springs 47, acting upon these valves, there is added the force of the fluid under high pressure. Therefore, there will be no danger of these valves permitting any flow of liquid into the low pressure or in-take manifold 53 on the working stroke of the piston 43.

Considering this same particular assembly and with the piston 43 performing a suction stroke, it will be seen that with the raising of valve 46, fluid is free to flow from the manifold 53, through the passage to the valve, past the latter and through passage 58 to the cylinder 38. At the same time, the high pressure valve 45 will be maintained in seated condition not alone by the spring 47, associated with such valve but also, incident to the action of the fluid under pressure which extends from the high pressure manifold 54, through passage 57 and is thus free to act on the upper face of valve 45.

Now, referring to the structure whereby the control rod 31 may be automatically shifted, it will be seen referring to Fig. 2, that the end of this rod terminates in an enlarged portion 59 upon which an anti-friction bearing of the thrust type 60 may be mounted. This bearing supports a follower 61 to which a piston extension 62 may be secured and which—in fact—may be integral with such follower. The extension 62 is concentrically disposed with respect to and spaced from rod 31. The piston portion of the same may take numerous different forms but having in mind, the high pressures which are being dealt with, it is preferred that the same include merely an inclined and relatively reduced surface 63. A channel 64 extends from the high pressure manifold to the cylinder in which the surface 63 rides. As will be seen the ends of this space are divided by packing assemblies which are maintained in position by a spacing element 63 which may be perforated for the passage of the fluid. Springs 65 are interposed between the follower 61 and the end of the housing 66 which encloses this follower. It is obvious with the foregoing structure, that as the pressure in manifold 54 increases, fluid will act against the piston surface 63 to retract the follower 61 and compress the springs 65. In so moving the parts, the rod 31 will be retracted. Due to the rack 30, the pinions 29 and 26 and the arcuate racks 25, it follows that the greater the pressure developed, the less will be the inclination of the swash-plate 21. While dealing with this phase of the matter, it will also be observed that the spacers 22 have extended portion 66 which project along the tubular shaft 16 and extend between the face of the same and the outer pinion element 26 to thus retain the latter in proper position.

With the plate 21 at a decreasing angle with respect to the plane of inclination which it normally occupies, it is obvious that the displacement of the pump is decreased. If the pressures continue to rise, the pump stroke and displacement would attain a zero value (with the swash-plate 21 in contact with stop 24) and would remain at such value until such time as the pressure in the system drops. Under these circumstances, the springs 65 would again function in view of the fact that the force exerted by them

would be greater than the fluid acting upon the control piston surface 63. Accordingly, the control rod 61 would shift and the swashplate would again begin to assume an angle such, that the piston strokes would cause sufficient displacement to maintain the pressure substantially static. If, of course, there is a tendency of the pressure to continue to drop, the springs will shift the follower 61 increasingly to the left as viewed in Fig. 2 until the swashplate finally assumes its maximum angle of inclination. Under these circumstances, a major displacement would occur. It is, of course, obvious that if an installation required a fixed stroke or in other words, a constant displacement at any given and predetermined R. P. M., a fixed-angle swashplate could be utilized. Conversely if no automatic control were desired, it is obvious that the control rod 31 might be manually adjusted.

It is apparent that the foregoing apparatus might also be employed as a motor by simply connecting the high pressure manifold as heretofore described with a source of high pressure fluid. Under these circumstances, and according to the particular arrangement of the parts, it is obvious that either a variable speed control or an automatic constant speed control would be incorporated in the motor.

From the foregoing it will be appreciated that among others, the several objects of the invention as specifically aforementioned are achieved. Obviously numerous changes in construction and re-arrangement of the parts might be resorted to without departing from the spirit of the invention as defined by the claims.

I claim:

1. A pressure apparatus including in combination, a body provided with a plurality of cylinders, a shaft rotatable with respect to said body, pistons coupled to said shaft and operating within said cylinders, said body being formed with two series of radially extending valve bores communicating with said cylinders, valve assemblies within said bores and comprising bodies and seat members, means forming a part of the same whereby a line seal is provided, an eccentric secured to said shaft and cooperating with said valves to shift the same as said shaft rotates with respect to said body, means responsive to the fluid pressures within said cylinders for varying the amount of travel of said pistons and means tending normally to cause said pistons to have a maximum path of travel whereby a maximum amount of fluid will traverse said cylinders.

2. A pressure apparatus including in combination, means providing a plurality of cylinder bores, pistons operable within said bores, a shaft rotatable with respect to said cylinders, a second shaft telescoped over said first shaft, a swash-plate encircling said shaft, a pin mounting said plate and extending through said shafts for coupling the same against movement with respect to each other, a pinion rotatably mounted by said shaft, rack members meshing with the teeth of said pinion and secured to said plate and a rack-bar extending into the interior of said shaft and meshing with said pinion for rotating the same.

3. A pressure apparatus including in combination, means providing a plurality of cylinder bores, pistons operable within said bores, a shaft rotatable with respect to said cylinders, a second shaft telescoped over said first shaft, a swash-plate encircling said shaft, a pin mounting said

plate and extending through said shafts for coupling the same against movement with respect to each other, a pinion rotatably mounted by said shaft, rack members meshing with the teeth of said pinion and secured to said plate, a rack-bar extending into the interior of said shaft and meshing with said pinion for rotating the same and spacing members interposed between said plate and pin, said spacing members extending adjacent said pinion to maintain the latter in position.

4. A pressure apparatus including a shaft, a swashplate pivotally secured to said shaft, pistons connected to said plate, means providing a cylinder, a further piston reciprocable within said cylinder and presenting a reduced inclined area upon which, fluid under pressure may act, means connecting said piston with said plate to vary the angularity of the latter in response to the force exerted by the former and spring means for normally maintaining said piston in a fully retracted position and said swashplate in a position of predetermined angularity with respect to said shaft.

5. A pressure apparatus including in combination a plurality of cylinders, a shaft rotatable with respect to said cylinders, pistons reciprocable within said cylinders and coupled to said shaft, each of said cylinders being formed with and connected to valve bores, valve assemblies disposed within said bores and governing the flow of fluid through the same, valve operating means secured to and movable with said shaft, means connecting said last named means with said assemblies whereby, as said shaft rotates with re-

spect to said cylinders, said assemblies will be operated, means responsive to the fluid pressure within said cylinders or automatically varying the amount of travel of said pistons within said cylinders, and means tending normally to cause said pistons to have a maximum path of travel whereby a maximum amount of fluid will traverse said cylinders.

6. A pressure apparatus including in combination a body provided with a plurality of cylinders, a shaft rotatable with respect to said body, pistons reciprocable within said cylinders, means coupling said pistons with said shaft, whereby said pistons will move in response to rotation of the latter, means forming a part of said coupling means and whereby the path of travel of said pistons may be varied, said body being formed with openings through which fluid may flow to and from said cylinders, valve means for controlling the flow of fluid through said openings, means secured to said shaft and connected to said valve means to shift the same as said shaft rotates with respect to said body, means responsive to the fluid pressures within said cylinders and connected to the means which couples said pistons with said shaft for automatically varying the amount of travel of said pistons within said cylinders, and means tending normally to cause said pressure responsive means to assume a predetermined position such that said pistons will have a predetermined zone of travel and a predetermined amount of fluid will traverse said cylinders.

ELIAS ORSHANSKY, JR.
BENHAM SACKETT POND.
